(57) **CLAIM**

The ornamental design for a front portion of a vehicle, as shown and described.

DESCRIPTION

FIG. 1 is a front and left side perspective view of a front portion of a vehicle showing our new design;

FIG. 2 is a front elevation view thereof;

FIG. 3 is a left side elevation view thereof;

FIG. 4 is a right side elevation view thereof;

FIG. 5 is a bottom plan view thereof; and,

FIG. 6 is a top plan view thereof.

The back of the front portion of a vehicle forms no part of the claimed design.
